UNITED STATES PATENT OFFICE

94,664

DESIGN FOR A GRAVE MARKER

Irwin W. Cox, Denver, Colo.

Application December 10, 1934, Serial No. 54,385

Term of patent 14 years

To all whom it may concern:

Be it known that I, Irwin W. Cox, a citizen of the United States, residing at the city and county of Denver, and State of Colorado, have invented a new, original, and ornamental Design for a Grave Marker, of which the following is a specification, reference being had to the accompanying drawing, forming part thereof.

Fig. 1 is a front elevation of a grave marker looking in the direction of the arrow 1 in Figure 2, showing my design;

Fig. 2 is an end elevation of the grave marker looking in the direction of the arrow 2 in Fig. 1; and

Fig. 3 is a perspective view thereof.

The predominant feature of my design consists in the ornamental effect produced by the combination of a bronze tablet and a stone base of the particular configuration and in the manner shown.

I claim:

The ornamental design for a grave marker, as shown and described.

IRWIN W. COX.
